UNITED STATES PATENT OFFICE.

CHARLES DE MINICO, OF PORTSMOUTH, OHIO, ASSIGNEE, BY MESNE ASSIGNMENTS, TO UNITED SHOE MACHINERY CORPORATION, OF PATERSON, NEW JERSEY, A CORPORATION OF NEW JERSEY.

SOLE-LEVELING MACHINE.

1,266,000.

Specification of Letters Patent. Patented May 14, 1918.

Application filed August 2, 1915. Serial No. 43,244.

To all whom it may concern:

Be it known that I, CHARLES DE MINICO, a citizen of the United States, residing at Portsmouth, in the county of Scioto and State of Ohio, have invented certain new and useful Improvements in Sole-Leveling Machines; and I do hereby declare the following to be a full, clear, and exact description of the invention, such as will enable others skilled in the art to which it appertains to make and use the same.

The present invention relates to sole leveling machines and more particularly to machines having a coöperating sole leveling roll and shoe supporting jack which are relatively movable in a longitudinal direction.

One object of the present invention is to prevent the leveling operation from bending the outstanding margin of the sole into close proximity to the upper and to maintain a substantially uniform thickness of sole edge. With this object in view a feature of the invention consists in the combination of a leveling roll, a shoe supporting jack, actuating mechanism for the roll and jack, and a sole edge support projecting beneath the outstanding margin of the sole to support the sole during the operation of the leveling roll.

A further object of the invention is to provide an improved form of sole edge support which is particularly adapted to machines of this type and may be conveniently adjusted to conform with different styles of shoes.

With the above objects in view further features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 represents a side elevation of a leveling machine embodying the several features of the invention; Fig. 2 is a detail illustrating upon an enlarged scale a side elevation of the sole edge support mounted upon the toe post of the shoe supporting jack; Fig. 3 is a detail showing a plan view of the sole edge support in operative relation to a shoe; Fig. 4 is a detail showing a cross section of the sole edge support taken

upon the line 4—4 of Fig. 2; and Fig. 5 is a detail illustrating a front elevation of the common adjusting mechanism for the toe support and sole edge support.

In leveling machines which employ a co-operating leveling roll and shoe supporting jack which are relatively movable to change the relative longitudinal position and lateral inclination of the roll and jack it is desirable that the outstanding margin of the sole shall be supported against the pressure of the leveling roll in order to prevent the bending of the sole margin into close proximity to the lasted upper and to maintain a substantially uniform thickness of sole edge. To this end the present invention contemplates the provision of means for positively supporting the outstanding margin of the sole in a predetermined position during the leveling operation.

The present invention is shown in connection with a leveling machine of a well-known form having a shoe supporting jack indicated generally at 1 and journaled upon a rock shaft 2 supported in the front portion of the machine frame. The rock shaft 2 is actuated by suitable mechanism consisting of a cam 3 mounted upon a cam shaft 4, and operative connections between the cam and rock shaft to impart the proper movements to the jack. The leveling roll is indicated at 6 and is mounted to vibrate in a roll carrier 7 secured to a sleeve rotatably supported in a roll carrying bed 8 which is pivotally mounted at 9 in the upper rear portion of the machine frame 10. The inclination of the roll relative to the jack is varied automatically during the operation of the machine by actuating mechanism connected with the roll carrier 7. The above described mechanism specifically forms no part of the present invention and is fully disclosed in the application of Baxter, Ser. No. 750,326, filed February 24, 1913, and in consequence has been only briefly described herein.

The shoe supporting jack shown in the present invention consists of a bed 15 having a toe post 16 formed integrally therewith, and a heel post 17 slidably supported thereon. The heel post carries the usual last pin and actuating mechanism and is adjustable toward and from the toe post to adjust the jack for varying sizes of shoes in a man-

ner well-known to those skilled in the art. In order to support the outstanding margin of the sole during the operation of the machine a sole edge support is conveniently arranged to project beneath the margin of the sole of a shoe supported upon the jack. In the illustrated embodiment of the invention this sole edge support is mounted upon the toe post and may be conveniently adjusted for varying styles of soles. The toe post 16 carries a toe rest 18 which is adjustably connected with the toe post by a sliding wedge 20 which moves in a slotted head 21 supporting and forming a part of the toe rest. The wedge 20 is conveniently operated through an adjusting screw 22 and hand wheel 23. With this construction, upon a rotation of the hand wheel a bodily vertical adjustment of the toe rest 18 relative to the toe post 16 is secured. In order to position the sole edge support in a predetermined relation to the toe rest the support is conveniently mounted upon the movable head 21. As shown clearly in the drawings, the sole edge support embraces the forepart of the shoe adjacent to the toe and is provided with a continuous engaging face projecting entirely about the toe and adjustable to conform to varying shapes of shoes. The sole edge support is carried by a pair of brackets 25 and 26 respectively secured to opposite sides of the head 21. The two brackets may be adjusted with relation to one another and to the head 21 through the provision of bolts 27 passing through elongated slots 28 formed in the brackets and threadedly engaging in the head 21. The sole edge support proper comprises a pair of members 30 and 31 pivoted together at 32 upon an arm 33 which is secured to the upper portion of the bracket 25. The arm 33 may be adjusted in two directions relative to the bracket 25 through the provision of a block 34 interposed between the arm 45 and bracket and having coöperating tongue and groove connections with the arm and bracket respectively extending at right angles to one another. The arm 33 is secured in adjusted position relative to the bracket by a bolt 35 threadedly engaging with the bracket and passing through elongated slots formed in the arm 33 and block 34. The members 30 and 31 are also supported midway between their ends by standards 36 and 37 which are slidingly supported upon an inclined table 39 formed upon the upper portion of the bracket 26. The standards 36 and 37 are moved toward and from one another and are retained in adjusted position by an adjusting screw 40 journaled in a bearing 41 secured upon the table 39 and having oppositely threaded portions 42 and 43. The adjusting screw is retained against longitudinal movement in the bearing by oppositely disposed collars

44 and 45, and is conveniently rotated by a knurled thumb nut 46. With this construction a rotation of the adjusting screw moves the standard toward and from one another, locking the members 30 and 31 about the pivot pin 32. Each of the members 30 and 31 is conveniently connected with its corresponding standard by a sleeve 47 which receives the reduced end of the standard and is secured by a fastening 48 to its respective member. With this construction a swivel connection is provided between each standard and the cooperating member, permitting an angular movement of the member relative to the standard when the members are adjusted toward and from one another. The bearing 41 is conveniently secured to the table 39 by a depending lug 50 formed upon the bearing and projecting through an elongated slot formed in the table, the bearing being secured in place upon the table by a nut 51 threadedly mounted on the lower end of the lug 50. It will be noted that the inclination of the table 39 conforms substantially with the inclination of the forepart of the sole when supported upon the jack, and thus an adjustment of the sole edge support in the direction of the length of the shoe does not cause a displacement of the sole edge support vertically with relation to that portion of the sole with which it engages. Furthermore, it will be noted that owing to the provision of the various adjustments substantially a universal adjustment of the sole edge support with relation to the shoe may be obtained. In order to cause the sole edge support to exert a substantially uniform pressure tending to resist the thrust of the leveling roll and to prevent the marring or disfiguring of that portion of the shoe with which the support engages the two members are provided with a continuous facing 52 supported by the members and extending about the forepart of the shoe to support the outstanding margin of the sole.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is;

1. A leveling machine, having in combination, a leveling roll, a shoe supporting jack, mechanism for changing the relative longitudinal position and lateral inclination of the roll and jack, and a sole edge support projecting beneath the outstanding margin of the sole to support the sole during the operation of the leveling roll.
2. A leveling machine, having in com-

- bination, a leveling roll and a shoe supporting jack comprising a toe post and a heel post, and a sole edge support mounted upon the toe post and arranged to project beneath the outstanding margin of the sole.
3. A leveling machine, having in combination, a leveling roll, a shoe supporting jack having a toe post and a heel post, a sole edge support mounted upon the toe post and arranged to project beneath the outstanding margin of the sole, and means for adjusting the sole edge support to cause the support to conform to different shapes of shoes.
- 15 4. A leveling machine, comprising, a toe post, a head mounted upon the toe post, a pair of oppositely disposed sole edge supporting members fulcrumed upon the head and arranged to project beneath the edge 20 of the sole when in operative position, and means for adjusting the two members toward and from one another to accommodate varying classes of work.
5. A leveling machine, comprising, a toe post, a pair of sole edge supporting members fulcrumed upon the toe post and arranged to project beneath the edge of the sole when in operative position, a standard supporting the free end of each of the members, and means for moving the standards bodily toward and from one another.
- 25 6. A leveling machine, comprising a leveling roll, a toe post, a pair of sole edge supporting members fulcrumed at one end 30 and having sole engaging faces arranged to support the outstanding margin of the sole against the pressure of the leveling roll, mechanism for adjusting the two members about the fulcrum, and means for securing a bodily vertical adjustment of the sole 40 edge support relative to the toe post.
7. A leveling machine comprising a toe post, a toe rest vertically adjustable with relation thereto, a sole edge support carried by the toe rest, and means for adjusting the support laterally with relation to the toe rest.
8. A leveling machine comprising a toe post, a toe rest vertically adjustable with relation thereto, a pair of sole edge supporting members carried by the toe rest, 50 means for adjusting the members toward and from one another, and means for adjusting the members lengthwise of the shoe.
9. A leveling machine comprising a toe post, a toe rest, a sole edge support, means for adjusting the toe rest and sole edge support vertically with relation to the toe post, and connections between the toe rest and sole edge support to provide for vertical 60 and lateral adjustments of the sole edge support relative to the toe rest.
10. A leveling machine comprising a toe post, a toe rest and a sole edge support carried thereby, and means for securing a simultaneous vertical adjustment of the sole edge support and toe rest relative to the toe post.

CHARLES DE MINICO.
